UNITED STATES PATENT OFFICE.

JULES ZUMBÜHL, OF BASEL, SWITZERLAND.

TRANSPOSING DEVICE FOR KEYED INSTRUMENTS.

Application filed February 26, 1925, Serial No. 11,769, and in Germany March 10, 1924.

This invention relates to transposing devices for keyed musical instruments, of the kind in which the wrest-plank or string-plate is capable of being shifted sideways 5 by means of a device through a certain number of semitones, so as to enable the same members of the key mechanism to play in a higher or lower key.

With cross-stringed instruments this arrangement has shown the need of improvement in view of the interposition of the hammer action between the keyboard and the string-plate, in order to allow the movement to the desired pitch to be effected correctly 10 and safely. For this purpose according to the present invention the hammer action is so connected with the string-plate, that it can be shifted together with the same relatively to the keys, so that it always participates, therefore, in the movements of the string-plate. In this way the hammer action always keeps the same position with relation 15 to the stringing of the string-plate. Only through this invention a cross stringed piano 20 becomes transposable by shifting the string-box base or string-plate, the new feature consisting in the simultaneous displacement of the hammer action.

The accompanying drawing illustrates by 25 way of example an embodiment of this improvement.

Figure 1 is a front view and

Figure 2 a cross section thereof.

Figure 3 shows on an enlarged scale a 30 cross section of the playing mechanism.

The string-plate *a* with the diagrammatically indicated stringing *b* is supported above and below by roller guides so as to be able to move sideways. Its movement is effected by means of a short toothed rack *c* and a pinion *d* which can be rotated from in front. It is held in its positions by a spring 35 pressed bolt *e* which engages notches in the toothed rack *c*.

On the string-plate *a* by means of the frame *f* is fastened the hammer action of known type indicated generally by *g*, so that it participates in the sideways movement of the string-plate.

The hammer action *g* is operated through the medium of transmission bars *h* (Figure 3) connected to the usual rocking levers *m* and guided by short links *n* carried by a supporting beam *o* mounted on the frame *f*. The transmission bars *h* project below out of the frame *f* and terminate at their lower end in a socket *i* for a tappet ball *r*. The bars *h* are arranged side by side as well as their ball sockets *i* which in this way constitute an uninterrupted series of tappet pieces placed above the rear ends of the key levers *k*. When a key lever *k* is actuated, its rear end raises the corresponding transmission bar *h* which, through its rocking lever *m*, operates the corresponding hammer device. As there is no positive connection between the key levers *k* and the corresponding transmission bars *h*, the frame *f* together with the hammer action and the actuating bars *h* can easily be displaced sideways with the movable string-plate without being hindered by the key levers. Indeed, when the frame *f* is displaced sideways, the balls *r* at the lower end of the bars *h* ride or roll freely over the rear ends of the key levers *k*, which thus in their normal position do not interfere with said displacement, as will be easily understood from Figures 1 and 3.

What I claim is:

In a keyed musical instrument a board of 80 keys, a movable string-plate, an intermediate hammer action and means for connecting the hammer action to the string-plate so that it is movable therewith relatively to the keys.

In witness whereof I have hereunto signed 85 my name this 14th day of February, 1925.

JULES ZUMBÜHL.
